Primary Examiner — Cynthia Underwood(74) Attorney, Agent, or Firm — Griffiths & Seaton PLLC;
 JoAnn M. Seaton(57) CLAIM

The ornamental design for salad serveware, as shown and described.

DESCRIPTION

FIG. 1 is a front, perspective view of salad serveware showing our new design;

FIG. 2 is a front view thereof, the rear view being a mirror image of the front view;

FIG. 3 is a right side view thereof;

FIG. 4 is a left side view thereof;

FIG. 5 is a top view thereof; and,

FIG. 6 is a bottom view thereof.

The dash-dash broken lines represent environment and form no part of the claim. The long dash-short, dash lines represent a boundary of the claim and form no part of the claim.

1 Claim, 6 Drawing Sheets(56)
